Co., Inc.

UNITED STATES PATENT OFFICE.

EDWIN FRANCIS IVES, OF WALLINGFORD, CONNECTICUT.

COTTER-PIN EXTRACTOR.

Application filed November 28, 1921. Serial No. 518,408.

To all whom it may concern:

Be it known that I, EDWIN FRANCIS IVES, a citizen of the United States, residing at Wallingford, in the county of New Haven 5 and State of Connecticut, have invented a new and useful Improvement in Cotter-Pin Extractors; and I do hereby declare the following, when taken in connection with the accompanying drawings, and the characters 10 of reference marked thereon, to be a full, clear, and exact description of the same, and which said drawings constitute part of this application, and represent in

Fig. 1 a side view of a cotter-pin extractor 15 constructed in accordance with my invention.

Fig. 2 an edge view of the same.

Fig. 3 a top or plan view thereof.

Fig. 4 a sectional view on the line 4—4 20 of Fig. 1.

Fig. 5 a perspective view of one of the hook-plates, detached.

Fig. 6 a perspective view of one of the fulcrum-plates, detached.

25 This invention relates to improvement in cotter-pin extractors, and particularly to extractors of the plier type. The object of this invention is to produce a cotter-pin extractor containing in itself duplicate parts, 30 whereby the life of the tool is prolonged and providing a device by which cotter-pins may be firmly gripped and readily removed, and the invention consists in the construction as hereinafter described and particu- 35 larly recited in the claims.

In carrying out my invention, I employ two handle-members 10 and 11. These are struck up from sheet-metal and are U-shaped in cross-section, and in the folded 40 edges each is formed with a series of notches 12, which provide a firm grip for the hand and fingers. At their outer ends, these handles are provided with curved bearing surfaces 13 adapted to rock one upon the 45 other. Mounted in the outer end of one of the handles 10 are two fulcrum-plates 14 and 15 secured by a bolt 16. These fulcrum-plates are curved at their ends to form fulcrum-points 17. Mounted in the 50 outer end of the other handle 11 is a pulling-plate 18 on a bolt 19, this plate being in the form of a bell-crank lever, one arm 20 being in the form of a pulling-hook, which may pass between the fulcrum-plates 55 14 and 15, the other arm 21 extending down-

ward between the fulcrum-plates 14 and 15, where it is held in place by the bolt 16, and serves to properly space the fulcrum-plates, so that the hook 20 may pass between their outer ends. The plate is also formed with 60 an arm 22, to which a spring 23 is attached, the other end of the spring being fixed to a bolt 24 extending through the handle 11. Mounted upon a bolt 25, which passes through the outer end of the handle 10 and 65 through the fulcrum-plates 14 and 15, and on each side of the handle, are plates 26 and 27,—duplicates of the plate 18, these plates being connected to the opposite sides of the handle 11 by the bolt 24.

70 The tendency of the spring 23 is to separate the handles and pass the hook 20 between the outer ends of the fulcrum-plates 14 and 15, and in position to be inserted into the eye of a cotter-pin, the points 17 75 of the fulcrum-plate providing a fulcrum or bearing, so that, when the handles are brought together, the downward movement of the hook with respect to the fulcrums will extract a cotter-pin. It will be noted that 80 the handles are so proportioned that their ends rock one upon the other, thus removing the strains which might be imposed upon a pivot if the handles were pivoted together.

85 By forming the handles with the notches 12, a firm grip is secured, and in case either of the fulcrum-points break or become worn away, these fulcrum-plates 14 and 15 may be reversed side for side, or end for end, as 90 each plate has four fulcrum-points. The hook 20 of the plate 18 is a part most liable to become bent or broken, and this plate 18 may be exchanged with either of the plates 26 or 27,—thus three hooks are provided.

95 I, therefore, not only produce a tool specially designed for the purpose of extracting cotter-pins, but provide that tool with interchangeable renewable parts. This tool 100 also becomes a combination tool, as a small nut or bar may be gripped between the edges 28 of the handle 10, and the hooks 20 of the plates 26 and 27; or a tube or rod may be gripped between the hooks 20 of the plates 105 26 and 27 and the edges 29 of the handle 11, as there is a slight rocking movement of the plates 26 and 27 with respect to the handle 11, which will be sufficient to grip an article, or a tube or rod supported by the 110

hook 20 of the plates 26 and 27 may be gripped between the edges 28 and 29 of the handles.

I claim:

- 5 1. A cotter-pin extractor, comprising two handle-members, fulcrum-plates mounted between the sides of one handle, a hook-plate mounted between the sides of the other handle, said hook-plate formed with a hook and with an arm extending downward between the said fulcrum-plates, and plates connecting the said handle-members.
- 10 2. A cotter-pin extractor, comprising two handle-members formed at their outer ends with rocking bearing faces, fulcrum-plates mounted between the sides of one handle-member, a hook-plate mounted between the sides of the other handle-member, said hook-plate provided with a hook and with an arm extending downward between the said fulcrum-plates, plates arranged on opposite sides of the handle-members and connecting

their outer ends, and a spring connected with a hook-plate and with the handle-member in which it is mounted.

3. A cotter-pin extractor, comprising two handle-members formed from sheet-metal, U-shaped in cross-section and formed with notches in their outer edges, fulcrum-plates mounted in the outer end of one of the handle-members, a hook-plate mounted in the outer end of the other handle-member, said hook-plate comprising a hook and an arm extending downward into engagement with the other handle-member, and plates corresponding to the hook-plate connecting the said two handle-members.

In testimony whereof, I have signed this specification in the presence of two subscribing witnesses.

E. FRANCIS IVES.
